UNITED STATES PATENT OFFICE.

MARCUS O. ANTHONY, OF NEW YORK, N. Y., ASSIGNOR TO A. KIMBALL COMPANY, OF NEW YORK, N. Y., A CORPORATION OF NEW YORK.

PACKAGING MACHINE.

1,412,098.

Specification of Letters Patent. Patented Apr. 11, 1922.

Application filed February 14, 1920. Serial No. 358,672.

To all whom it may concern:

Be it known that I, MARCUS O. ANTHONY, a citizen of the United States, and resident of New York, county of New York, State 5 of New York, have invented an Improvement in Packaging Machines, of which the following description, in connection with the accompanying drawing, is a specification, like characters on the drawing representing like parts.

This invention relates to improvements in means for forming unit packages of superimposed articles and comprises mechanism adapted to present a binder, preferably in the form of a substantially flat strip, to said articles and to bend said binders around said articles in such a manner as to clamp them firmly together.

A further object of the invention is to 20 provide a unit packaging machine of the type described having means for forming upon the ends of the binder interengaging means adapted, when the binder is applied to the articles, to form a locked seam, unit- 25 ing the ends of the binder.

A further object of the invention is to provide a carrier having means for automatically presenting successively groups of superimposed articles to the binder applying mechanism, and more specifically, successively to the binder forming and the binder applying mechanisms whereby a rapid and substantially automatic operation of the machine may be attained.

A further object of the invention is to 35 provide a novel means for intermittently actuating the carrier and for locking the carrier in the predetermined positions in which the holders for the superimposed 40 articles may present said articles properly to the binder forming and binder applying means.

The invention is disclosed herein as embodied in a machine for forming unit packages of jar rings, such as are used in usual 45 types of glass fruit jars, and in other analogous relations.

Rubber rings for jars and the like have heretofore either been packed in cartons or 50 wrappers, or have been secured together by a wire bent around a number of superimposed rings, the ends of the wire being bent around the inner walls of the rings and permitted to remain loosely against them.

The wires when thus used frequently cut

the rings and furthermore do not form sufficiently permanent binders to retain the rings in proper condition.

The present invention contemplates the use, preferably of a substantially flat binder 60 formed of or comprising a material which when bent will have a permanent set, the means for applying the binder to the rings being of such character that the ends of the binder are caused to interlock to form a 65 locked seam which lies closely adjacent the inner walls of the superimposed rings.

Preferably a plurality of such binders are applied to each set or pile of superimposed rings which may be assembled in 70 uniform numbers, such as a dozen to each package. The binders desirably may be applied at diametrically opposite portions of the rings, thereby preventing the rings from separating and providing a package which 75 can be easily handled and transported.

The invention contemplates various other novel features of construction and arrangement which will more fully appear from the 80 following description and the accompanying drawings and will be pointed out in the annexed claims.

The preferred embodiment of the invention is disclosed in the accompanying drawing, in which,

Fig. 1 is a side elevation of a machine for 85 forming unit packages of a series of superimposed rings.

Fig. 2 is a detail view of means for locking the intermittently movable carriage.

Fig. 3 is a front elevation of a machine.

Fig. 4 is a plan view of a machine, certain portions being omitted and a portion of the carrier broken away.

Fig. 5 is a detail elevation of the binder 95 forming mechanism, the holder and carrier for the rings being shown in vertical section.

Fig. 6 is an enlarged side elevation of the binder bending and locking mechanism; also showing a portion of the carrier and 100 one of the holders in vertical section.

Fig. 7 is a detail vertical sectional view illustrating the binder bending mechanism as bending the binder transversely around the superimposed rings.

Fig. 8 is a similar view showing the binder bending and locking formers acting to bend the binder against the inner walls of the rings and in the position of locking the seam.

105

110

Fig. 9 is a vertical sectional view of a unit package of superimposed rings.

The machine for forming a unit package of superimposed articles embodying my invention comprises an intermittently movable carrier having a series of holders for the superimposed articles with means for actuating the same to present the holders, carrying the superimposed articles, successively to forming mechanism for producing a locking joint in the end or ends of the binders and then to binder bending mechanism which acts to bend the binders first across the upper and lower faces of the pile of superimposed rings and then to complete the bending of the binder around the superimposed articles and to lock the ends of the binders together.

Any suitable form of binder may be employed. Preferably, however, the binder is in the form of a flat strip consisting of or comprising pliable material which is capable of a permanent set when bent. A desirable binder consists of two narrow strips of paper secured together with a reinforcing wire therebetween, such as is illustrated in Patent No. 1,073,828, granted to Wallin Sept. 28, 1913.

The preferred embodiment of the invention which is illustrated herein as a machine for forming unit packages of superimposed rings, such as rings for jars, comprises a base supporting a frame having a vertical web 2 having an inverted U-shaped upper portion 3 provided with horizontally disposed bosses 4 and 5 in which are mounted the stems of the clamping and bending formers, and vertically disposed bosses 6 and 7 in which are mounted the stems or plungers of the formers which complete the bending and interlock the ends of the binders.

The frame is also provided with a vertical boss 8 which forms the journal for a shaft 45 which supports a rotatable carrier or table 9 which is provided with a series of holders, for the superimposed rings or other articles to be bound together, to form the unit package.

The holders comprise base portions 10 having semi-cylindrical sections 11 extending vertically, upwardly therefrom and spaced apart to provide slots 12 through which the binders may be bent around the superimposed articles. Complementary groove binder supports 13 are adjustably secured adjacent to the ends of the semi-cylindrical sections of the holders, the same being spaced apart just far enough to receive the edges of the binder strips between them and to hold the binders in vertical position alongside the outer walls of the superimposed rings.

The upper faces 14 of the holders form a seat for the lowermost rings while members,

preferably pins 15 extending upwardly therefrom, engage the inner walls of the rings and prevent them from displacement. The rings may be applied to the holders manually or automatically and the binders likewise may be inserted in the binder supports 13 manually or automatically, and when inserted therein rest at their lower ends upon the upper face of the base 10.

The base 10 desirably is provided at the 75 slots 12 with upwardly extending portions 16 which engage the inner sides of the ends of the binders to insure the proper positioning of the same alongside the superimposed rings and which also act as die members to form flanges upon the lower ends of said binders in a manner which will herein-after be more fully set forth.

When the superimposed rings have been placed upon the holders and binders inserted 85 in the binder supports, which are preferably located diametrically opposite, the holders are presented to forming mechanism which crimps a groove in the upper end of the binder adapted to interlock with the flange 90 which is formed upon the lower end of said binder.

The mechanism for thus crimping the upper ends of the binders comprises a bracket 17 which is secured to a rectangular boss 18 upon the U-shaped member 3 of the frame, said bracket having integral downward extensions 19 and 20 to which are secured hardened dies 21 and 22 having recesses 23 and 24 of suitable form to provide a notch 100 in the ends of the formers. The complementary die members comprise projections 25 and 26 secured to, or integral with arms 27 and 28 of bell crank levers one of which is pivotally mounted upon a stud 29 extending 105 laterally from the bracket 17, the other being secured to a shaft 30 which is mounted in suitable bosses on said bracket.

The bell crank levers are provided respectively with arms 31, 32 extending toward each other, the adjacent ends being connected together by a link 33. The die members 25, 26 are normally withheld from cooperative engagement with the dies 23, 24 by a helical spring 34 which is secured at its 115 ends to suitable studs upon the arms 27, 28 of the bell crank levers. In order to actuate the dies 25, 26 the shaft 30 is provided with an arm 35 which is engaged by a screw 36 which is adjustably seated in a bracket 37 120 carried by a link 38 which is reciprocated by suitable mechanism. In the present construction the link 38 is actuated by the same mechanism which serves to reciprocate the upper bending and locking former as will 125 hereinafter be more particularly described.

In the operation of the former the downward movement of the link 38 acting through the pin 36 rocks the arm 32 and shaft 30, thereby rocking the bell crank lever causing 130

its arms 28 to force the die 26 into the complementary die recess 24 and thereby to crimp one of the binder strips. As the shaft 30 is rocked, the other arm 32 of the bell 5 crank lever acts through the link 33 to rock the other bell crank lever and cause its arm 27 to force the die 25 into cooperative relation to the die 23 thereby crimping the end of the other binder strip.

10 When the binder strips have been thus crimped at their upper ends, the upward movement of the link 38 withdraws the pin 36 from engagement with the arm 35 of the rock shaft, thus enabling the spring 34 to draw the arms 27 and 28 of the bell crank lever toward each other, thereby removing the dies 25, 26 and releasing the upper ends 15 of the binder strip. The carrier is then actuated to move the holder from the station at which the ends of the binder strip are crimped to the binder applying station in which the binders are bent around the superimposed articles and the ends of said binders locked together.

20 25 The mechanism for bending binders transversely across the upper and end faces of the superimposed articles or rings comprises a former, or preferably a plurality of formers, having means for clamping the 30 binders against the outer walls of the superimposed articles and bending means for bending the binders.

35 In the preferred embodiment of the invention illustrated herein two formers are illustrated as diametrically oppositely disposed in relation to the superimposed series 40 of rings. One of these formers comprises a head 39 having upper and lower jaws 40, 41, adapted to pass respectively above the face 45 of the uppermost ring and below the face of the lowermost ring, said jaws desirably being provided at their ends with anti-friction 50 rollers. The head 39 is carried upon a shaft 42 which is slidably mounted in the boss 4. A clamping plunger 43, adapted to engage the outer walls of the superimposed rings, is located between the jaws 40, 41 and provided with a stem 44 which extends axially into the shaft 42 of the former and 55 engages the end of a helical spring 45 located in the axial bore in said shaft 42. The spring 45 abuts at its opposite end against a screw threaded plug 46 seated in the end of said shaft 42.

60 55 The head 39 of the former is provided with a laterally extending stud which is connected by a link 47 to a stud upon the upper end of an arm 48 of a bell crank lever which is pivotally mounted upon a stud 49 extending laterally from the web 2 of the main frame. The other arm 50 of said bell crank lever has at its end a cam following roller 51 which engages a suitable groove in a face cam 52 which is carried by a cam shaft 53 mounted in suitable

bearings, in brackets 54, 55 mounted upon and extending upwardly from the base 1 of the machine.

The former, which is disposed oppositely to that above described, is of the same general construction and comprises a head 56 having upper and lower jaws 57, 58 adapted respectively to pass above the face of the uppermost ring and below the face of the lowermost ring, said head being mounted 70 upon a shaft 59 which is slidably mounted in the boss 5. A plunger 60, having a stem 61 extending axially into the shaft 59, is normally pressed forward by a helical spring 62 located in the axial bore in said 75 shaft and held therein by a screw threaded plug 63 in the end of said shaft.

The head 56 is actuated simultaneously with the head 39 through a link 64 which is pivotally connected at one end to a stud 65 80 extending laterally from the jaw 57 and at its opposite end is provided with a stud 66 which engages a slot in the arm 67 of a bell crank lever which is pivotally mounted 85 upon a stud 68 projecting laterally from a boss 69 on the main frame. The other arm 70 of said bell crank lever is connected by a link 71 to an arm 72 of the rock shaft 49 which is actuated through the arm 50 by the cam 52. By reason of this connection it 90 will be readily understood that both the formers for clamping the binder against the sides of the rings and for bending the binders across the upper and lower faces of the rings are actuated simultaneously from the 95 same cam.

The lower jaws 41 and 58 of the bending formers desirably have downwardly projecting end portions 73, 74 respectively which, in cooperation with the upwardly 100 extending portions 16 of the holders, bend the lower ends of the binder strips outwardly to form flanges which are adapted to engage the V-shaped grooves which are crimped in the upper ends of the binders 105 and when thus engaged to lock the ends of the binders together.

When the ends of the binders are thus bent to embrace the upper and lower faces of the rings they are acted upon by upper 110 and lower formers which complete the bending of the binders around the rings and secure the ends thereof together.

The lower former comprises a head 75 carried upon a shaft or stem 76 which is 115 slidably mounted in the boss 7. The lower end of the stem 76 has secured to it a collar 77 having a laterally projecting stud 78 which is connected by a link 79 to the end of a lever 80 which extends longitudinally 120 of the main frame and is pivoted at its opposite end upon a stud 81 carried in a suitable boss 82 projecting from the main frame. The lever 80 is provided intermediate of its ends with a laterally extend- 125

ing stud carrying a cam following roller 83 which engages a cam groove in the inner face of a cam 84 which is fixedly secured to the cam shaft 53.

5 The upper former comprises a head 85 which is fixedly secured upon a shaft 86 slidably mounted in the boss 6 and has secured to its upper end a collar 87 which is connected by a laterally extending stud 88 10 to the upper end of the link 38. The lower end of the link 38 is connected to the end of a lever 89 which is pivotally mounted upon a stud 90 projecting from a suitable boss from the main frame. The lever 89 is 15 provided intermediate of its end with a stud 91 to which is connected the upper end of a link 92 having a slot 93 embracing the shaft 53 and its lower end provided with a cam following roller 94 which engages a 20 suitable cam groove in a cam 95 which is fixedly secured upon the cam shaft 53.

The former heads 75 and 85 desirably may be provided with anti-friction rollers adapted to engage the binder strips as the 25 formers advance to perform their functions. The cams for actuating the upper and lower plungers are so designed that the lower plunger advances at first more rapidly than the upper plunger and bends the lower end 30 of the binder alongside the inner walls of the rings so that when the upper former forces the upper end of the binder downwardly the V-shaped notch, which has been crimped in the upper end of the binder, 35 will interlock with the flange projecting from the lower end of the binder. The plungers then come closely adjacent to each other and pinch the V-shaped upper end of the binder upon the flanged lower end of 40 the binder. The lower plunger then recedes and the upper plunger is forced downwardly sufficiently to bend the joint formed by the interlocking upper and lower ends of the binder downwardly alongside the wall of 45 the rings as illustrated in Fig. 9.

Any suitable mechanism may be employed for actuating the carrier or table intermittently to present the holders successively first to the binder crimping station and then 50 to the binder applying station. In the preferred mechanism disclosed herein, in which the carrier is illustrated as in the form of a table, the intermittent movement is imparted to the table by a pawl and ratchet mechanism. In this construction the periphery of the table is provided with a series of notches 96 which are adapted to be engaged by a spring actuated pawl 97 which is pivotally mounted upon a stud 98 upon the end 55 of an arm 99 of a bell crank lever which is pivoted upon a reduced portion of the hub of the table 9.

The other arm 100 of said bell crank lever is provided at its end with an arcuate segment 60 65 101 having upon its under face a rack

102, the teeth of which extend downwardly and engage the teeth of a sector 103 at the upper end of a lever 104 which is pivotally mounted at its lower end upon a stud 105 projecting laterally from a bracket 106 on 70 the base 1.

The lever 104 is provided intermediate of its ends with a laterally extending stud 107 which is connected to the end of a link 108, the opposite end of which is provided 75 with a slot 109 which embraces the shaft 53. The link 108 is provided intermediate of its ends with a laterally extending stud having upon it a cam roller 110 which engages a cam 111 on the cam shaft 53. The cam 111 is so constructed and timed with relation to the other cams, which are carried by the same cam shaft, as to reciprocate the link 108 and thereby oscillate the sector 103 at times when the forming plungers are at rest, 80 so that the holders may be moved readily from one station to the next.

It is essential that means shall be provided for preventing an overthrow of the carrier reciprocating-mechanism and for retaining the holders in exactly the right position in relation to the formers. Consequently a locking mechanism for the table has been provided. The preferred form of locking mechanism illustrated herein comprises a bolt 112 which is slidably mounted in a suitable boss 113 in a bracket secured to the web 2 of the main frame, the bolt 112 being forced upwardly by a suitable spring 114 into engagement with suitable recesses 100 in the under-face of the table 9. The bolt 112 is provided with a downwardly extending stem 115 having a laterally extending pin 116 projecting through a slot 117 in the boss 113, the pin 116 being provided with 105 a pivotally mounted end portion 118 which forms one member of a switch cam for actuating the bolt 112. The other member of the switch cam comprises a cam 119 projecting laterally from the sector 103. The lower 110 face of the cam is adapted upon movement of the sector 103 outwardly—that is to the right as illustrated in Fig. 1—to engage the upper face of the extension 118 of the pin 116, thereby depressing the bolt 112 and 115 releasing the table. The action of the sector in oscillating the rack carrying arm 101 thereby enables the pawl 97, by engagement with the notch 96 in the periphery of the table, to rotate the table sufficiently to advance the holders from one station to the next. As the sector 103 is thus advanced the end of the pin 118 rides off of the cam and permits the bolt to be pressed by its spring 114 against the under-face of the table so 120 that when the next succeeding notch is reached the bolt 112 will drop in it and lock the table against further rotation.

When the sector 103 is oscillated in the opposite direction the upper face 120 of the 130

switch cam engages beneath the pivotally mounted end 118 of the pin 116 and merely raises said end so that the bolt 112 is not actuated by the return movement of the 5 sector.

When the sector 103 has moved beyond the pin 116 the pivoted end 118 thereof drops again to horizontal position where it is ready to be engaged by the face 119 10 of the switch cam upon the next forward movement of the sector 103.

Any suitable mechanism may be provided for rotating the cam shaft 53. Desirably, however, a stop mechanism is introduced in 15 said driving mechanism in order to enable the operation of the machine to be readily controlled. As illustrated herein the shaft 53 is driven through a worm gear 121 which meshes with a worm 122 upon the shaft 123 20 of a suitable motor, means being provided for releasably connecting the worm gear 121 to the shaft 53 and for stopping the rotation of the shaft 53 immediately upon dis-engagement from the worm gear. Suitable 25 lever mechanism is provided for actuating the clutch and stop mechanism, but inasmuch as this particular stop mechanism is not a necessary part of the machine a detailed description thereof is not necessary.

30 In the operation of the machine a uniform number of rings, such as a dozen, are placed upon the holders by operators standing alongside the machine. The same, or another, operator then drops a binder strip 35 into each of the binder supports at the sides of the holders. The intermittent movement of the carrier eventually positions one of the holders, with the rings superimposed upon it, at the crimping station whereupon 40 the crimping dies are actuated to form V-shaped notches in the upper ends of the binders. Further intermittent movement of the carrier brings the holders, with the binders thus formed, to the binder applying station.

45 When this station is reached the diametrically disposed, horizontally operating formers clamp the binder against the sides of the rings. At the same time the jaws advance to bend the upper and lower ends of 50 the binder horizontally across the upper and lower faces of the rings. As the lower jaws advance they engage the binder strip and, in cooperation with the upwardly extending flange 16 of the holder, form a lateral flange 55 upon the lower end of the binder. When the horizontally operating formers have bent the ends of the binder to horizontal position they are withdrawn and the upper and lower formers advance; the lower former advancing 60 more rapidly than the upper, bends the lower ends of the binders alongside the inner walls of the rings. The upper binder then forces the upper ends of the binder downwardly, causing the V-shaped upper end to 65 interlock with the flanged lower end of the

binder. The upper and lower formers are then forced towards each other sufficiently to squeeze the V-shaped end portion of the binder tight upon the flanged lower end portion. The lower former then recedes and 70 the upper former advances sufficiently to bend the inter-engaged ends of the binders downwardly thereby forming a locked seam such as is illustrated in Fig. 9.

75 It will be understood that the embodiment of the invention disclosed herein is of an illustrative character and is not restrictive and that various modifications in construction and arrangement of parts may be made within the spirit and scope of my invention. 80 It will also be understood that whereas the invention is disclosed herein as comprising a machine in which the articles and the binders are presented to the holders manually, an automatic mechanism for effecting this 85 purpose may be utilized for this purpose.

Having thus described my invention, what I claim as new and desire to secure by Letters Patent, is:

1. A machine for forming a unit package 90 of superimposed articles secured together by a binder having its ends provided with complementary means adapted to be interlocked, comprising a holder for the superimposed articles, means operable to bend 95 the binder around the superimposed articles and to cause the complementary means at the ends of said binder to interlock.

2. A machine for forming a unit package 100 of superimposed articles secured together by a binder having its ends provided with complementary means adapted to be interlocked, comprising a holder for said superimposed articles, means for supporting a binder adjacent to said superimposed articles, means for bending said binder around 105 said superimposed articles and interlocking the ends of said binder.

3. A machine for forming a unit package 110 of superimposed rings secured together by a binder, having its ends provided with complementary means adapted to be interlocked, comprising a holder for said superimposed rings, means for supporting a binder adjacent the periphery of said rings, means for bending the binder across the top and bottom of said rings and means for bending the end portions of the binder upon the inner walls of said superimposed rings and for interlocking the end portions of said binder. 115

4. A machine for forming a unit package 120 of superimposed rings connected together by a plurality of binders having complementary interengaging end portions, comprising a holder for said superimposed rings, a plurality of binder supporting means upon said holder, formers acting to bend said binders across the top and bottom of said rings, formers acting to bend the ends of said binders alongside the inner walls of said 125 130

rings and to interlock the end portions thereof to form a locked seam and means for actuating said formers.

5. A machine for forming a unit package of superimposed rings, comprising a holder for said rings, means for holding a binder adjacent the outer walls of said superimposed rings, a side former having a yieldably clamping plunger adapted to hold the 10 binder against the outer walls of said rings, and jaws positioned to bend said binder across the upper and lower faces of said superimposed rings, upper and lower formers operable to bend the end portions of 15 said binder into engagement with the inner walls of said superimposed rings, and means for actuating said formers.

6. A machine for forming a unit package of superimposed rings, comprising a holder 20 for said rings, means on said holder for supporting a binder adjacent the outer walls of said superimposed rings, means for forming a notch in the upper end of said binder, a side former having a yieldable clamping 25 plunger adapted to hold said binder against the outer walls of said superimposed rings and jaws positioned to bend said binder across the upper and lower faces of said superimposed rings, said lower jaw being 30 adapted, in cooperation with the holder, to form a flange upon said binder, upper and lower formers operable to bend the end portions of said binder into engagement with the inner walls of said superimposed rings 35 and to cause locking and inter-engagement of the flange and notched ends of said binder and to unite the same to form a locked seam, and means for actuating said formers.

7. A machine for forming a unit package 40 of superimposed rings connected together by a binder having complementary interengaging end portions, comprising a carrier having a plurality of holders for said rings, binder forming means, binder applying 45 means, means for actuating said carrier intermittently to present said holders containing superimposed rings successively to said binder forming means, and said binder applying means, and means for actuating said binder forming and applying means.

8. A machine for forming a unit package of a series of superimposed articles, comprising a rotatable carrier having a plurality of holders for said superimposed articles, 55 means for applying a binder to said articles in a holder when the latter is in a predetermined position and means for actuating said carrier to present said holders successively to the binder applying means.

60 9. A machine for forming a unit package of a series of superimposed articles, comprising a rotatable carrier having a plurality of holders for said superimposed articles, means for applying a binder to said 65 articles in a holder when the latter is in a

predetermined position, means for actuating said carrier to present said holders successively to the binder applying means, including a pawl having means adapted to engage said carrier, and means for actuating said pawl. 70

10. A machine for forming a unit package of a series of superimposed rings, comprising a rotatable circular table having thereon a plurality of holders for said superimposed articles, means for applying a binder to the articles in a holder when the latter is in a predetermined position and means for rotating said table about its axis to present said holder successively to the binder applying 80 means, comprising a pawl carrying arm pivotally movable about the axis of said table, a pawl carried thereby adapted to engage said table, a rack carried by said pawl carrying arm, a toothed segmental member engaging said rack, and means for oscillating said segmental member in co-ordination with the action of the binder applying means. 85

11. A machine for forming a unit package of a series of superimposed rings, comprising a rotatable circular table having thereon a plurality of holders for said superimposed articles, means for applying a binder to the articles in a holder when the latter is in a predetermined position and means for rotating said table about its axis to present said holders successively to the binder applying 90 means, comprising a pawl carrying arm pivotally movable about the axis of said table, a pawl carried thereby adapted to engage said table, a rack carried by said pawl carrying arm, a toothed segmental member engaging said rack, means for oscillating said segmental member in co-ordination with the action of the binder applying 95 means, means for locking said table during the movement of said pawl carrying arm in one direction and means for releasing said locking means upon movement of said pawl carrying arm in the opposite direction. 100

12. A machine for forming a unit package of a series of superimposed rings, comprising a rotatable circular table having thereon a plurality of holders for said superimposed articles, means for applying a binder to the articles in a holder when the latter is in a predetermined position and means for rotating said table about its axis to present said holder successively to the binder applying means, comprising a pawl carrying arm pivotally movable about the axis of said table, a pawl carried thereby adapted to engage said table, a rack carried by said pawl carrying arm, a toothed segmental member engaging said rack, and means for oscillating said segmental member in co-ordination with the action of the binder applying means, a spring actuated locking bolt adapted to lock the table against 115 rotation during the action of the binder ap- 120

130

plying means, a switch cam mechanism carried by said bolt and said segmental member adapted to cause the withdrawal of said bolt upon movement of the segmental member in one direction and to permit said bolt to be retained by its spring in locking engagement with said table during the movement of the segmental member in the other direction.

10 13. A machine for forming a unit package of a series of superimposed rings, comprising a travelling carrier having a plurality of holders provided with diametrically oppositely disposed binder supporting means, means for imparting an intermittent movement to said carrier, binder applying means, and binder forming means positioned in front of said binder applying means, and means operable by said binder applying

20 means to actuate said binder forming means.

14. A machine for forming a unit package of a series of superimposed rings, comprising a travelling carrier having a plurality of holders provided with diametrically oppositely disposed binder supporting means, means for imparting an intermittent movement to said carrier, binder applying means, binder forming means comprising diametrically oppositely disposed stationary dies positioned to receive the upper ends of binders for said superimposed rings, expansible die members positioned to cooperate with said stationary dies, and means for actuating said expansible die members.

25 30 35 15. In a machine for forming a unit package of superimposed articles, comprising a holder for the superimposed articles having means for supporting a binder adjacent to

the walls of said articles, a former having jaws provided at their ends with rollers 40 adapted to engage the binder and force the same across the faces of the uppermost and lowermost articles, and means for actuating the former.

16. In a machine for forming a unit package of superimposed articles, comprising a holder for the superimposed articles having means for supporting a binder adjacent to the walls of said articles, a former having jaws provided at their ends with rollers 50 adapted to engage the binder and force the same across the faces of the uppermost and lowermost articles, and means for actuating the former, and a spring actuated plunger carried by said former adapted to engage 55 said binder and hold the same firmly against the walls of said articles during the bending operation.

17. In a machine for forming a unit package of superimposed rings, comprising a holder for said rings, supporting means for binders disposed upon diametrically opposite sides of said holder, a pair of formers disposed at diametrically opposite position with respect to said rings and having jaws 60 65 adapted to engage said binders and bend the same over the upper and lower faces of said rings, plungers yieldably mounted in said formers intermediate of said jaws adapted to engage and clamp the binders 70 against the walls of said rings and means for actuating said formers.

In testimony whereof, I have signed my name to this specification.

MARCUS O. ANTHONY.
